Primary Examiner — Mary Ann Calabrese*(74) Attorney, Agent, or Firm* — Nelson Mullins Riley & Scarborough, LLP(57) **CLAIM**

The ornamental design for a token reader housing, as shown and described.

DESCRIPTION

FIG. 1 is a front perspective view of a token reader housing showing our new design;

FIG. 2 is a front view of the token reader housing of FIG. 1; FIG. 3 is a right side view of the token reader housing of FIG. 1;

FIG. 4 is a left side view of the token reader housing of FIG. 1;

FIG. 5 is a rear view of the token reader housing of FIG. 1; FIG. 6 is a top plan view of the token reader housing of FIG. 1; and,

FIG. 7 is a bottom plan view of the token reader housing of FIG. 1.

The broken lines of FIGS. 4, 5 and 7 are illustrative of the visible environmental structure of the token reader housing and form no part of the claimed design.
